UNITED STATES PATENT OFFICE.

ELIAS H. COWART, OF PLEASANTON, CALIFORNIA.

SAFETY-TURNBUCKLE.

SPECIFICATION forming part of Letters Patent No. 752,524, dated February 16, 1904.

Application filed February 19, 1903. Serial No. 144,159. (No model.)

To all whom it may concern:

Be it known that I, ELIAS H. COWART, a citizen of the United States, residing at Pleasanton, in the county of Alameda and State of California, have invented certain new and useful Improvements in Safety-Turnbuckles; and I do hereby declare the following to be a full, clear, and exact description of the invention, such as will enable others skilled in the art to 10 which it appertains to make and use the same.

My present invention is an improvement in turnbuckles which are links used for setting up and tightening rods or stays employed usually in marine construction. To be more 15 specific, however, my invention is a safety-turnbuckle, which as the name signifies is designed to add the additional feature of security and safety to requisites of the ordinary turnbuckle. It is a well-known fact among those 20 familiar with the action of this class of devices that after the buckle is set up tight the constant tension of the tightened rods will gradually turn the buckle back until it eventually becomes necessary to retighten the parts. 25 In fact, constant inspection of the buckle is necessary. Now by the employment of my device this accidental loosening is absolutely prevented and the parts once set up are held relatively stationary. I have not overlooked 30 the requisites of strength and durability nor the matter of economy and simplicity of construction.

I am enabled to accomplish the above results by the means illustrated in the accompanying drawings, in which—

Figure 1 is a perspective view of the complete buckle, showing the relative positions of the parts of my improvement. Fig. 2 is a transverse section taken in the direction of 40 the arrows in Fig. 1.

I will now set forth the general construction of my invention and subsequently explain the operation of the same, reference being had to the above views by letter.

The main link A of the buckle is formed in the usual manner with the right-hand and left-hand threaded terminals B and C and the parallel connecting-bars D and E. The inner 45 extremities of the rods F and G, which engage the threads in terminals B and C, are cut down to a square cross-section. Formed 50 with perforations to engage each of the squared

ends of rods F and G are the twin plates H and I, their diametrically opposite ends being notched to receive and slide on bars D and E. 55 Now it will be seen from the above description that after the buckle has been set up until the rods F and G are taut and the plates H and I are moved along the bars D and E until they engage with the squared end of the rods the 60 buckle and rods are held relatively stationary and any accidental loosening absolutely prevented. When it is desired to loosen the buckle, the split pins a and b, which are provided to hold plates H and I in place, are re- 65 moved and the plates drawn from the rods.

In order to permit the plates H and I being placed between the bars D and E, I have cut the grooves in the plates sufficiently deep, as shown in Fig. 2, to allow the canting of plate 70 sufficient to pass the bars.

By the improved construction herein shown and described I am enabled to manufacture and place on the market a simple and positively secure turnbuckle at a moderate cost, 75 and thus to meet the demands of the trade.

I am aware that changes in the form and proportion of parts of the devices herein shown and described as an embodiment of my invention can be made without departing from the 80 spirit or sacrificing the advantages thereof, and I therefore reserve the right to make such changes, substitutions, and alterations as fairly fall within the scope of my invention.

What I claim, and desire to secure by Letters Patent, is—

A turnbuckle formed with parallel bars connecting the opposite right-hand and left-hand threaded members thereof, one or more members situated between said bars and having 90 their opposite edges notched to receive said bars, said members being formed with central square perforations, and opposite rods to engage the threads of said buckle and having their inner ends formed to enter said perforations, said notched members being arranged to slide on said parallel bars substantially as and for the purpose set forth.

In testimony whereof I affix my signature in presence of two witnesses.

ELIAS H. COWART.
